UNITED STATES PATENT OFFICE

CHARLES F. FRIEDRICH, OF ROCHESTER, NEW YORK, ASSIGNOR TO E. E. FAIRCHILD CORPORATION, OF ROCHESTER, NEW YORK, A CORPORATION OF NEW YORK

DESIGN FOR A BOX

Application filed July 14, 1931. Serial No. 40,546. Term of patent 3½ years.

To all whom it may concern:

Be it known that I, CHARLES F. FRIEDRICH, a citizen of the United States, residing at Rochester, in the county of Monroe and State of New York, have invented a new, original, and ornamental Design for a Box, of which the following is a specification, reference being had to the accompanying drawings, forming part thereof.

In the drawings:

Fig. 1 is a front view of a box showing my new design;

Fig. 2 is a rear view;

Fig. 3 is a view of one side of the box, the other side of the box being identical with that shown in the drawing.

Fig. 4 is a view of one end of the box, the other end of the box being identical with that shown in the drawing.

The colors are lined in the drawings.

I claim:

The ornamental design for a box as shown and described.

CHARLES F. FRIEDRICH.
